UNITED STATES PATENT OFFICE.

JAMES J. HOOD, OF PONDER, GEORGIA, ASSIGNOR OF TWENTY-FIVE PER CENT. TO
SARAH A. SAXON, OF PONDER, GEORGIA.

CIRCUIT-CLOSER FOR LOCKS.

1,347,039.

Specification of Letters Patent. Patented July 20, 1920.

Application filed July 3, 1918. Serial No. 243,241.

To all whom it may concern:

Be it known that I, JAMES J. Hood, a citizen of the United States, residing at Ponder, in the county of Union and State of Georgia, have invented certain new and useful Improvements in Circuit-Closers for Locks; and I do hereby declare the following to be a full, clear, and exact description of the invention, such as will enable others skilled in the art to which it appertains to make and use the same.

This invention relates to improvements in burglar alarm locks and has for one of its objects the provision of a device of this character whereby an alarm will be given upon retracting the locking bolt indicating that an unauthorized person is opening the lock or the object to which the lock is applied.

Another object of this invention is the provision of a keyhole guard adapted to actuate the alarm when moved to uncover the keyhole.

A further object of this invention is the provision of a burglar alarm lock of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description, and accompanying drawings, in which:

Figure 1 is a front elevation of a burglar alarm lock constructed in accordance with my invention,

Fig. 2 is a vertical sectional view of the same,

Fig. 3 is a longitudinal sectional view taken on the line 3-3 of Fig. 2,

Fig. 4 is a detail sectional view taken on the line 4-4 of Fig. 2,

Fig. 5 is a detail sectional view illustrating one of the contact poles,

Fig. 6 is a detail sectional view illustrating spaced contacts, and

Fig. 7 is a detail sectional view of a ratchet wheel.

Referring in detail to the drawings, the numeral 1 indicates a lock casing having the removable front wall 2 adapted to be secured to the casing by suitable fastening elements passing through the openings 3. 60 A latch bolt 4 is slidably mounted within the casing 1 and has its head 5 normally disposed exteriorly of the casing for engagement with the keeper (not shown) while the opposite end of the latch bolt is bifurcated 65 to form a pair of relatively spaced arms 6 having shoulders 7 formed upon the ends thereof. A knob spindle 8 extends through the casing 1 and has mounted thereon a member 9 that overlies the arms 6 and in 70 engagement with the shoulders 7 whereby upon rotating the knob spindle 8 by the usual knobs 10, the latch bolt will be retracted against the tension of a spring 12. The spring 12 is secured to a lug 13 carried by the casing and has its other end disposed within a notch 14 formed within the latch bolt. The casing 1 has an opening 15 below the latch bolt 4 to slidably receive the locking bolt 16. The locking bolt 16 is 80 provided with an elongated slot 18 to receive a lug 19 carried by the casing wherein the lock bolt is slidably supported within the casing. The rear end of the locking bolt 16 is provided with a cut away portion 85 20 for the purpose of receiving an ordinary key of any desired character inserted through the keyhole 21 of the casing 1 to move the locking bolt 16 into engagement with a keeper (not shown) or to retract 90 the same. If desired, suitable guards (not shown) may be placed about the keyhole 21 within the casing 1 for the purpose of making it necessary to use a particular type of key in order to operate the locking bolt 16. 95 The locking bolt has its lower edge provided with a shoulder 21 forming spaced notches 22 adapted to be engaged by the end of a leaf spring 23 carried by a lug 24 formed in the casing. This spring 23 is 100 adapted to hold the locking bolt 16 against accidental movement when in either of its positions.

A shaft 25 is journaled in the casing 1 and in a suitable bracket 26 carried by the 105 casing and has formed thereon an arm 27 disposed in rear of the locking bolt 16 and which is adapted to be engaged by the locking bolt when said bolt is retracted for rotating the shaft 25. A shaft 28 is jour-

naled in the casing 1 adjacent the shaft 25 and has a coil spring 29 mounted thereon. One end of the coil spring is secured to the shaft while the opposite end extends forwardly and rests upon the shaft 25 placing the shaft 28 under the tension of the spring. An arm 30 is carried by the shaft 25 and has its forward end curved as illustrated at 31 and rests upon an arm 32 carried by the shaft 28 while the opposite end of the arm 30 rests upon the convolutions of the spring 29. By having the arms 30 and 32 in engagement with each other, the tension of the spring 29 holds the arm 27 just rearwardly of the locking bolt 16 so that when the locking bolt 16 is retracted, the arm 27 is moved rearwardly rotating the shaft 25 moving the arms 31 and 32 laterally which also turns or rotates the shaft 28. An arm 33 is carried by the shaft 28 and is disposed over a contact 34. The contact 34 is connected to a pole 35 carried by the casing 1 and insulated therefrom. A contact 36 is carried by a pole 37 supported by the casing and insulated therefrom and is normally spaced from the contact 34 at its free end.

The arm 33 being disposed over the contact 34 will move said contact in engagement with the contact 36 upon retracting the locking bolt 16 thus completing an electric circuit to an alarm 38. The alarm 38 has connected thereto conductors 39 and 40. The conductor 39 is connected to the pole 37 while the conductor 40 is connected to a battery or other electrical source 41 which has connected thereto a conductor 42 connected to a suitable switch 43. The switch 43 is connected to the pole 35 by a conductor 44 so that when the switch 43 is in a closed position and the locking bolt 16 is retracted the electric alarm 38 will be sounded. A member 45 is carried by the casing and is disposed over the contact 34 for the purpose of limiting the movement of said contact in its proper position in relation to the contact 36.

A shaft or spindle 46 is journaled in the casing 1 and carries upon one end a circular guard plate 47 provided with a slot 48 in the shape of a keyhole adapted to be moved into registration with the keyhole 21 so that a key may be inserted within the casing 1 for the purpose of actuating the locking bolt 16. The slot 48 is normally out of registration with the keyhole 21 so that the plate overlies the keyhole and prevents a key from being inserted therein. The spindle or shaft 46 is provided with a suitable hand grip 49 for the purpose of rotating the same. Oppositely disposed grooves 50 are formed upon the shaft or spindle 46 to receive oppositely disposed lugs 51 formed upon a cam 52 so that the cam is locked to the spindle or shaft 46 for rotation therewith and is located within the cas-

ing 1 and adjacent the contact 34 so that when the cam is rotated the prominent portion thereof will engage the contact 34 causing the contact to move laterally and as it moves laterally the lug 53 engages the contact 36 completing the electric circuit to the alarm 38. The alarm at this instant being sounded by the rotation of the shaft or spindle 46 to align the slot 48 with the keyhole 21. A ratchet wheel 54 is formed upon the cam 52 and is normally engaged by a pivoted dog 55 carried by a member 56 mounted upon the casing 1. The dog 55 is normally urged into engagement with the ratchet wheel 54 by means of a spring 57 so that the guard plate 47 and spindle or shaft can be rotated only in one direction.

While I have shown and described the preferred embodiment of my invention, it will be understood that minor changes in construction, combination, and arrangement of parts may be made without departing from the spirit and scope of the invention as claimed.

Having thus described my invention what I claim is:

1. A device of the character set forth comprising a casing, a locking bolt slidable in said casing, tension means for said locking bolt, spaced contacts carried by said casing, a shaft journaled in said casing, a second shaft journaled in said casing, tension means for said second shaft, an arm carried by said second shaft and in engagement with one of the contacts, means establishing a connection between the shafts, and an arm carried by said first shaft and adapted to be engaged upon the retraction of the locking bolt to cause the latter arm to move the contacts through the above named means in engagement with each other.

2. A circuit closer for locks comprising a casing, a locking bolt in said casing, a shaft journaled in said casing, a second shaft journaled in said casing, a coil spring carried by the second named shaft and having one end secured thereto and its other end disposed against the first named shaft, an arm carried by the first named shaft and having one end disposed at right angles, an arm carried by the second named shaft and underlying the right angled end of the first named arm, a third arm carried by the second named shaft and disposed at right angles, spaced contacts carried by said casing, one of said contacts disposed adjacent the last named arm, and an arm carried by the first named shaft and adapted to be engaged by the locking bolt when retracted to move the contacts through the above named means in engagement with each other.

3. A circuit closer for locks comprising a casing, a locking bolt slidable in said casing, spaced contacts carried by said casing,

means located in said casing for moving the contacts in engagement with each other upon the retraction of said bolt, a shaft journaled in said casing, a keyhole guard carried by 5 said shaft, a cam carried by said shaft and adapted to move the contacts in engagement with each other upon rotation of said shaft, a ratchet wheel carried by said shaft, and a spring actuated dog carried by said casing

and engaging the ratchet wheel to allow the 10 key guard to be rotated only in one direction.

In testimony whereof I affix my signature in presence of two witnesses.

JAMES J. HOOD.
